MULTIPLE PAN SET

Joseph G. Jackson, Oak Park, Ill., assignor to
The Edward Katzinger Company, Chicago, Ill.,
a corporation of Illinois

Application February 21, 1938, Serial No. 191,644

3 Claims. (Cl. 53—6)

This invention relates to a multiple pan set of the type commonly referred to as a muffin pan set wherein a series of pans are arranged in spaced relation and secured together by a relatively broad, flat mounting frame of sheet metal or the like, having depending flanges at its periphery to form a rim substantially coextensive in height with the depth of the pans surrounded thereby.

10. Among its other objects, the present invention contemplates a multiple pan set of this type including the formation of a supporting rim at the periphery of the set and the reinforcement and protection of the face of the mounting frame adjoining said rim.

15. It is also an object of the present invention to provide tying members between the rims at opposed edges of the set which will span the space between transversely aligned rows of the 20 pans and support the body or face of the mounting frame in said region.

With the above and other objects in view, as 25 will be apparent, this invention consists in the construction, combination and arrangement of parts, all as hereinafter more fully described, claimed and illustrated in the accompanying drawing, wherein:

30. Fig. 1 is a fragmentary plan view of a multiple pan set with an edge or rim construction as contemplated by this invention.

Fig. 2 is an enlarged fragmentary side elevational view of the set shown in Fig. 1.

Fig. 3 is an enlarged fragmentary vertical section taken on line 3—3 of Fig. 1.

35. Fig. 4 is a fragmentary vertical section taken on line 4—4 of Fig. 2.

Fig. 5 is a fragmentary bottom plan view of the set as shown in Fig. 1.

Fig. 6 is an enlarged fragmentary vertical section taken on line 6—6 of Fig. 5.

40. Heretofore, in the construction of muffin pan sets it has been customary to create a bead at the lower edges of the flange or rim depending from the periphery of the mounting frame. In other 45 instances, the flange or rim has been surrounded by means composed of an iron strap which bears against the upright face of the flange to be secured thereto in any suitable manner. This type of rim construction provides no reinforcement for the body or upper face of the mounting frame adjoining the rim and usually does not provide for protecting the corners of the face of the mounting frame against abrasive wear incident to handling of the set in commercial 50 practice.

The present invention has in view the reinforcement of the rim of the mounting frame in such a manner that the rim is not only substantially stiffened but the face of the mounting frame adjoining said rim is protected against deformation as well as abrasive wear.

Reference being had more particularly to the drawing, 10 represents a frame consisting of a relatively broad, flat piece of sheet metal of the type commonly employed in the manufacture of 55 muffin pan frames, having a plurality of openings of a transverse dimension slightly less than the corresponding dimension of each pan element 11 mounted therein. The number of openings vary according to the number of pans which it is 10 desired to have in the frame. Likewise, the shape 15 or design of the openings is controlled by the shape of the pan elements used. As will be observed in Fig. 1, a seam 12 is created between the upper edges of the pans 11 and the edge of the 20 openings in the frame through which connection between the pans 11 and the frame 10 is established. It will be manifest however, that the set shown in the drawing may be modified by 25 employing a frame 10 having the pan elements 11 pressed or spun from the body of the frame without departing from the essence of this invention. The frame 10, at its periphery, is bent 30 downwardly at an angle to its body to create a flange 13 to form a part of the rim at the edge of the frame as hereinafter more fully described. Enclosed by said flange 13 and the underside of the mounting frame 10 is a brace of strap iron or 35 strip metal, the latter having a vertically disposed portion 14 resting flush against the inner surface of the flange 13 and a laterally disposed portion 15 in abutment with the underside of the pan mounting frame 10. Surrounding the outer face of the flange 13 is a clamping strap 17 of relatively heavy gauge stock, the latter being 40 secured to the flange 13 by rivets 16 piercing the portion 14 of the brace and the adjacent portion of the flange 13. The strap 17 may be made of a single strap bent to surround the periphery of the flange 13, or it may be made up in sections abutting or overlapping at their ends as shown in Figs. 2 and 4. In producing this type of joint, the strap sections are preferably cut away to create a tongue 18 at each end of the overlapping sections of the strap 17, and the tongue 18 of the 45 overlying section of the strap 17 is confined in a mutually depressed portion of the underlying section of strap 17, as more clearly shown in Fig. 4. Thus the sides or rim of the pan set may be 50 moved in sliding contact with the corresponding 55

surface of another set without encountering snagging of the sets. The ends of the brace enclosed by the flange 13 are also preferably constructed to overlap. To accommodate the formation of 5 such a joint of the ends of the brace, the laterally extending portion 15 of the brace is cut away on either side of the joint. Rivets 20, which pass through the tongues 18 of the strap sections to connect the same in rigid assembly, also enter the 10 flange 13 and the overlapping ends of the brace enclosed by the flange 13 to complete the union of the various elements.

The upper edge of the strap 17 is provided with a laterally projecting lip 21 which overhangs a 15 corresponding portion of the brace and the top marginal portion of the frame 10 adjoining the flange 13. To obtain a continuous flush face in this region, the body of the frame 10 may be countersunk as at 22 to compensate for the thickness 20 of the lip 21 of the clamping strap 17. Obviously, the triple-ply construction thus provided in the region of the top marginal portion of the frame 10 adjacent to the flange 13 creates a relatively stiff shoulder adapted to resist shearing 25 strain at the juncture of the flange 13 and the body of the mounting frame 10, as well as to eliminate abrasive wear on the exposed face of the frame 10.

The lower edge of the strap 17 is provided with 30 a lip 23 which underlies the bottom edge 24 of the edge portion 13 of the frame 10, as well as the bottom edge 25 of the brace enclosed by said flange or edge portion 13. The width of the strap 17 is preferably such as to locate its lip 35 23 in a plane substantially flush with the bottom of the pans 10. Consequently, slight variations in the depth or width of the flange 13 arising in the process of manufacture may be accommodated without altering the desired coplanar 40 relationship of the pan bottoms to the bottom limits of the strap 17.

Interposed between transversely aligned rows of pans 11 is a tying member or bar 26. This tying member 26 is preferably arranged in edge-wise abutment with the underside of the frame 45 10 and is secured thereto by clips 27 riveted as at 28 to the frame 10. Extensions 30 at each end of the tying member 26 are bent angularly to rest flush against the inner face of the brace 50 enclosed by the flange 13 of the frame 10 at transversely remote limits of the set and secured rigidly thereto by rivets 29 passing through the extensions 30, as well as the flange 13 and the brace and strap which enclose the flange 13. In 55 this manner the body of the frame 10 between the sides and ends thereof is braced both by the tying member 26 and the reinforced rim at the edges of the pan mounting frame 10, to provide a structure of maximum rigidity.

60 What is claimed is:

1. In a multiple pan set, a plurality of pans, a substantially flat sheet metal frame for mounting and uniting said pans in spaced relationship, the periphery of said frame being bent downwardly to create a flange, a brace having a 5 vertically disposed portion in contact with the inner surface of said flange and a laterally disposed portion in abutment with the underside of said frame, a clamping strap surrounding the outer surface of said flange and having portions 10 in overlying relation to a portion of the frame adjacent to said flange and in underlying relation to the lower limits of said flange and the brace enclosed thereby, means for securing said brace, flange and strap in rigid assembly, and 15 tying means extending between transversely aligned rows of said pans and in abutment with the underside of said frame, and secured thereto.

2. In a multiple pan set, a plurality of pans, a substantially flat sheet metal frame for mounting and uniting said pans in spaced relationship, the periphery of said frame being bent downwardly to create a flange, a brace having a 20 vertically disposed portion in contact with the inner surface of said flange and a laterally disposed portion in abutment with the underside of said frame, a clamping strap surrounding the outer surface of said flange, a lip at the upper edge of said clamping strap enclosing a portion of the upper face of said frame adjacent to said flange, 30 a lip at the lower edge of said clamping strap underlying said flange and said brace and substantially coplanar with the bottoms of said pans, a tying member extending transversely of and in abutment with the underside of said frame, 35 and means for securing said tying member to said flange including means for securing said flange brace and clamping strap in rigid assembly.

3. In a multiple pan set, a plurality of pans, a substantially flat sheet metal frame for mounting and uniting said pans in spaced relationship, the periphery of said frame being bent downwardly to create a flange, a brace in abutment with the inner face of said flange and having a 40 laterally disposed portion in abutment with the underside of said frame, a clamping strap surrounding the outer surface of said flange, a second clamping strap complementary to the clamping strap aforesaid to form a continuous clamping strap surrounding the periphery of the pan set, a tongue formed at the end of one of said straps, a mutually depressed portion in the meeting end of the other of said straps for receiving the tongue aforesaid, and means for securing said clamping strap, flange and brace in rigid 45 assembly including a rivet penetrating said tongue and mutually depressed portion in said straps.

JOSEPH G. JACKSON.
